(57) **CLAIM**

(21) Appl. No.: **29/127,071**

The ornamental design for a solo-mixer, as shown and described.

(22) Filed: **Jul. 28, 2000**

DESCRIPTION

(30) **Foreign Application Priority Data**

Jan. 28, 2000 (DE) 400 01 031

FIG. 1 is a left side perspective view of the solo-mixer;

(51) LOC (7) Cl. **31-00**

FIG. 2 is a rear view thereof;

(52) U.S. Cl. **D7/378**

FIG. 3 is a front view thereof; and

(58) Field of Search D7/376-386, 316-318;
366/64, 65, 96, 197, 199, 241, 244, 314

FIG. 4 is a left side view thereof.

(56) **References Cited**

FIG. 5 is a right side view thereof;

U.S. PATENT DOCUMENTS

FIG. 6 is a top view thereof; and,

D. 223,465 * 4/1972 De Puy D7/317

FIG. 7 is a bottom view thereof.
